UNITED STATES PATENT OFFICE

FREDERICK W. PITTS, OF DETROIT, MICHIGAN, ASSIGNOR TO MICHIGAN STEEL CORPORATION, OF DETROIT, MICHIGAN, A CORPORATION OF NEW JERSEY

APPARATUS FOR NORMALIZING STEEL SHEETS

Application filed January 28, 1929. Serial No. 335,643.

This invention relates to a method and apparatus for normalizing or heat treating steel sheets or the like.

An object of this invention is to provide a method of the above character in which the production may be considerably speeded up without in any way impairing the resulting product.

A further object of this invention is to provide a method of the above character which will prevent the burning or rashing of the steel sheets during their passage through the furnace and which will accordingly produce a more evenly treated sheet.

The invention has as a further object the provision of a furnace having an open end into which the sheets to be treated are introduced and having means for eliminating the cold area normally present adjacent the open

end of a furnace of this character.

Other objects and advantages of the invention as well as the numerous novel details of construction will become apparent as the following description proceeds, particularly when reference is had to the accompanying drawings wherein,

Figure 1 is a vertical sectional view through an end of a furnace constructed in accordance with the teachings of this invention,

Figure 2 is a horizontal sectional view taken substantially on the line 2-2 of Figure 1, and

Figure 3 is a transverse sectional view taken substantially on the line 3-3 of Figure 1.

Figure 4 is a sectional view taken on the line 4-4 of Figure 1.

In the normalizing or heat treating of steel sheets and the like it has been customary to convey the sheets to be treated through an elongated heating chamber. During the passage of the sheets through the chamber, the sheets have been subjected to the action of heating gases directed toward the upper faces of the sheets from burners arranged in the top of the heating chamber. These burners have been arranged at spaced points longitudinally of the chamber and it has been customary to introduce the sheets into the open

inlet end of the chamber and to remove the sheets from the open outlet end of the chamber after the same have been properly heat treated.

In a furnace of this character, however, difficulty has been experienced in preventing the formation of hot spots which tend to burn the sheets at certain points. A further difficulty has been encountered in the elimination of the cold area normally present adjacent the inlet end of the chamber. In other words, it has been found that the first fifteen or twenty feet of the heating chamber adjacent the inlet end thereof has been so cold as to be ineffective in the treating of the sheets, so that the actual heat treating or normalizing of the sheets has not been commenced until the sheets have been conveyed to a point within the heating chamber from fifteen or twenty feet from the inlet end thereof.

The present invention contemplates a method in which the sheets to be treated are passed through a heating chamber being introduced at the inlet end thereof and being removed from the outlet end of the chamber after they have been properly heat treated. The invention further contemplates the provision of burners arranged in the upper portion of the heating chamber for directing heating gases downwardly toward the upper faces of the sheets as they are conveyed through the heating chamber. All of this is in accordance with the old practice, but the present invention contemplates in addition to the above steps, the step of heating the underfaces of the sheets of steel immediately after they are fed into the inlet end of the heating chamber. In particular, the present invention contemplates the provision of a method wherein hot gases are directed toward the underfaces of the sheets of steel adjacent the inlet end of the heating chamber whereby the cold area normally present adjacent the inlet end of the furnace of the character described is eliminated, thus making the entire length of the heating chamber effective for the heat treating of the steel sheets.

While the method above described might be carried out in any one of a number of different ways, there is disclosed in the draw-

ings a furnace particularly adapted for carrying out the method described. Referring then particularly to the figures of the drawings, wherein like reference characters 5 designate corresponding parts throughout all views, the numeral 10 designates generally a furnace, the inlet end only of which is shown. As illustrated the furnace includes the side walls 11, top wall 12 and floor 13, which together 10 form an elongated heating chamber designated generally by the reference character 14. The numeral 15 designates the inlet end of the chamber 14, it being understood that the sheets 16 to be heat treated are fed 15 into the chamber 14 at 15 and are conveyed through the chamber to be discharged at the outlet end thereof (not shown).

For conveying the sheets 16 through the heating chamber 14, there may be provided 20 a plurality of shafts 17 journaled at spaced points longitudinally of the furnace in brackets 18, secured as at 19, to suitable uprights 20 arranged on opposite sides of the furnace. Secured to the shafts 17 are rollers 25 21 on which the sheets 16 are adapted to ride and for driving the shafts 17 each shaft is provided at its one end with a bevel gear 22 adapted to be driven from a main drive shaft 23 by a suitable gear 24. The shaft 23 extends 30 longitudinally of the furnace adjacent one side thereof and is driven by any suitable motor (not shown). The shaft 23 will carry a plurality of the gears 24 there being one gear for each shaft 17 so that all of the shafts 35 17 and the rollers 21 carried thereby will be driven in synchronism. Thus sheets of steel fed into the open end 15 of the chamber 14 and on to the rollers 21 will be conveyed longitudinally of the heating chamber for 40 discharge through the discharge end thereof, as will be readily understood.

For directing hot gases downwardly toward the upper faces of the sheets 16 as they pass through the heating chamber 14, there 45 are provided a plurality of oil burners 25 arranged at spaced points longitudinally of the furnace 10. These burners 25 are mounted in the side walls 11 of the furnace as clearly illustrated in Figure 3 of the drawings 50 so that the flames 26 issuing from the burners are directed inwardly toward the center of the heating chamber 14. In order that the flames 26 will be directed downwardly toward the sheets 16 the inner face of the top 55 12 of the furnace is arched as at 27, the arches being in the form of stepped surfaces adapted to deflect the flames downwardly toward the sheets 16, as will be readily apparent by reference to Figure 3 of the drawings. 60 The structure of the furnace as thus far described is substantially standard practice and forms no part of the present invention being merely illustrated for the purpose of more clearly bringing out the manner in 65 which the cold area adjacent the inlet end of

the furnace is eliminated. It will be understood that in practice the sheets 16 are fed into the chamber 14 from the end 15, being conveyed by the rollers 21 through the heating chamber during which time they are subjected to the hot gases deflected downwardly from the burners 25 by the arches 27. In actual practice it is customary to place each sheet 16 on a waste sheet 28 as clearly illustrated in the drawings in order to prevent contact of the sheets with the rollers 21. 70

As brought out before, it has been found that in a furnace of the character above described there has been a cold area adjacent the inlet end 15 of the furnace, this area extending from fifteen or twenty feet longitudinally of the furnace. The present invention contemplates the elimination of this cold area by the provision of burners located adjacent the inlet end 15 of the furnace, these burners being adapted to direct heating gases toward the underfaces of the sheets 16 during the initial portion of their passage through the furnace. 80

Referring then particularly to Figures 1 and 2 of the drawings, it will be noted that there is provided a pit 30 arranged adjacent the end 15 of the furnace. The pit 30 is arranged below the furnace and communicates directly with the heating chamber thereof, the floor 15 being cut away to permit this communication as will be readily apparent by reference to Figure 1. The pit 30 extends entirely across the furnace 10 and is provided with the rearward extension 31 communicating with a lateral extension 32 which extends outwardly beyond the side of the furnace, whereby access may be had to the pit 30 from the side of the furnace. There may be provided a ladder 33 in the extension 32 of the pit so that an attendant may conveniently enter the extension 32 of the pit and walk from this extension to the pit proper designated generally by the reference character 30. 90

The pit 30 is provided at its upper forward end with an extension 35 which extends longitudinally of the heating chamber 14 in the direction of travel of the sheets. This extension is below the rollers 21 and is provided with an arched or stepped floor 36 for a purpose hereinafter to be more fully described. Between the recess or extension 35 and the pit 30 there is provided a relatively low wall 37 in which are mounted a pair of oil burners or the like 38 having their nozzles directed inwardly toward the recess 35. 100

The hot gases and products of combustion from the burners 38 are directed upwardly by the stepped or arched floor of the recess and between the rollers 21 to heat the sheets 16 passing through the furnace. Each burner may be provided with a suitable valve 39 arranged within the pit 30 whereby the burners may be conveniently controlled from the said pit. 110

From the above it is believed that the structure and operation of the furnace will be readily apparent. In use, the sheets 16 superposed on the waste sheets 28 are fed into 5 the heating chamber at the inlet end 15 thereof. These sheets are carried through the furnace by the rollers 21 and are heated from above by the products of combustion from the burners 25 deflected downwardly by the 10 arches 27. Adjacent the inlet end 15 of the furnace the burners 38 are provided, the products of combustion of which are projected into the recess 35 from which they are deflected upwardly toward the sheets 16. Thus 15 that portion of the furnace adjacent the inlet end thereof will be heated and the cold area normally found adjacent the inlet end will be eliminated, making more effective this portion of the furnace. The pit 30 being ac- 20 cessible from the side of the furnace forms a convenient place from which the attendant may control the burners 38 to regulate the heat at the inlet end of the furnace in order that burning or rashing of the sheets will be 25 prevented.

While one method and one apparatus has been described with considerable detail, it is to be clearly understood that the description is for the purposes of illustration only. The 30 right is therefore reserved to make such changes in the details of construction and arrangement of parts as will fall within the purview of the attached claims.

What I claim as my invention is:

- 35 1. A furnace for normalizing articles including in combination an elongated chamber having a charge receiving end portion, means in said chamber for conveying the articles from the charge receiving end portion 40 aforesaid longitudinally of the chamber, means arranged at longitudinally spaced points upon opposite sides of the chamber and adjacent the upper portions thereof for effecting combustion in the chamber above the 45 articles passing therethrough, a baffle extending longitudinally of the chamber and projecting downwardly from the top wall thereof into the path of the products of combustion discharged by said last mentioned means 50 for deflecting the heating gases downwardly toward the articles passing through the furnace, a pit arranged below the chamber adjacent the charge receiving end thereof and having a portion extending longitudinally of 55 the chamber in the direction of travel of said articles, said portion terminating at the inner end thereof in an upwardly extending tapered wall forming a baffle, and means for effecting combustion in the extension afore- 60 said operable to impinge the products of combustion against said baffle whereby the heating gases are deflected upwardly toward the articles passing through the furnace.
2. In a furnace for normalizing a sheet of steel including in combination an elongated

open-ended heating chamber, means arranged at longitudinally spaced points adjacent the upper portion of the chamber for effecting combustion therein above the articles passing therethrough, a baffle extending longitudinally of the chamber and positioned in the path of the products of combustion for deflecting the same downwardly toward the upper surface of the articles passing through the furnace, a second chamber arranged below the first mentioned chamber in communication therewith and extending longitudinally thereof, means positioned in one end wall of the second mentioned chamber for effecting combustion in the direction of the movement of the articles and the opposite end wall fashioned for deflecting the products of combustion upwardly toward the under surface of the articles.

In testimony whereof I affix my signature. 85
FREDERICK W. PITTS.
